UNITED STATES PATENT OFFICE.

DON CARLOS WISENBERG, OF PERU, INDIANA.

ARTICLE HOLDER.

1,424,607.

Specification of Letters Patent. Patented Aug. 1, 1922.

Application filed May 31, 1921. Serial No. 473,898.

To all whom it may concern:

Be it known that I, DON C. WISENBERG, a citizen of the United States, residing at Peru, in the county of Miami and State of Indiana, have invented certain new and useful Improvements in Article Holders, of which the following is a specification.

This invention relates to improvements in article holding devices.

10 The primary object of the invention is the provision of an article holding device specifically adapted for holding fruit jars, and the like, to maintain the article being held in fixed position, for placing or removing 15 a cover thereon or therefrom, or to perform any other work upon the article being held.

A further object of the invention is the provision of an article holding device of the above described character, which may be 20 clamped to a supporting element, such as a table, and including novel operating means for moving jaws in increasing or decreasing circumferential alignment, to engage or disengage an article.

25 Other objects and advantages will be apparent during the course of the following detailed description.

In the accompanying drawings, forming a part of this specification, and in which 30 similar reference characters designate corresponding parts throughout the several views,

Figure 1 is a plan view of the improved article holding device.

35 Figure 2 is a plan view, of a supporting plate, showing several other elements in cross section.

Figure 3 is a side elevation of the improved article holding device, showing the 40 same engaging a jar.

Figure 4 is a fragmentary cross sectional view of the improved article holder, showing the cooperating details thereof.

Figure 5 is a plan view of a detail of the 45 invention.

Figure 6 is a perspective view of a jaw element used to engage an article.

In the drawings, wherein for the purpose of illustration is shown the preferred embodiment of my invention, the letter A designates a supporting base plate, having the turn table B rotatably mounted thereon. An operating lever handle C is oscillatively mounted upon the supporting base plate and 55 engaging the turn table for oscillation to expand or contract certain jaw elements D.

The improved article holder is provided with a supporting clamp E for maintaining the same in fixed position for operation.

The supporting base plate A is preferably 60 so shaped as to provide a circular disc portion 10 having a stem or shank 11 projecting radially thereof. The disc portion 10 is provided with a central aperture 12 for reception of a pivoting rivet or pin 13, whereby 65 the turn table B can be oscillatively or rotatably mounted thereon. A series of arcuate guide slots 14 are symmetrically cut about the pivot aperture 12, and struck therein eccentrically with respect to said aperture to provide cam guide slots, the purpose 70 of which will be subsequently described.

The turn table B is preferably circular in formation; the same having a diameter equal to the diameter of the disc portion 10 75 of the supporting base A. The turn table B is provided with a plurality of teeth 16, upon a portion thereof in segmental formation. A series of relatively straight slots 17 are cut radially therein, from the pivot- 80 element 13 as a center. A slot 17 is provided upon the turn table B, to cooperate with each arcuate slot 14 of the base plate A; said slots when the base plate A and turn table B are assembled, being so 85 arranged in intersecting relation to provide an opening, which can be moved to or from the pivoting element 13, by relative movement of the base plate A and turn table B.

The jaw elements D are provided for action through the slots in the base plate A and turn table B. They are arranged in circumferential alignment upon the turn table B; each comprising an upstanding channel shaped supporting portion 20, preferably arcuate in cross section, and provided with a resilient insert 21, preferably of rubber, fiber or the like. Each of the jaws D are moreover provided with the turn table engaging portion 22, provided to straddle 100 a slot 17 upon the turn table B, said portion 22 being provided with a suitable aperture 23 for insertion of a rivet or pivoting element 24; the pivoting element 24 of each of the jaws D normally projecting downwardly through a pair of intersecting slots 14 and 17 in the base plate A and turn table B respectively. The pivot element 24 is provided with a head 25 adapted to overlie the bottom of the base plate A and to 110 straddle the slot 14 therein.

In placing the jaws D upon the turn ta-

ble B, it is preferred that their resilient article engaging portions 22 be disposed to face the pivotal center 13 at all times. To this end, each of the jaw elements D have been provided with a downwardly projecting finger 27, upon the outer end of the plate engaging portion 22, for engagement within its respective slot 17 of the plate or turn table B.

10. The operating means C, preferably comprises a single handle 30, pivotally mounted adjacent an end thereof, through an aperture in the extreme end of the shank portion 11, and by a rivet 31 or the like. The 15 lever or handle 30, is provided with an enlarged portion 32, adapted for overlying the shank 11 adjacent the turn table B. This portion 32 is preferably segmental in formation, and provided with the teeth 33 upon its 20 arcuate end; the teeth 33 normally adapted to mesh with the teeth 16 of the turn table B. It is preferred that the handle 30 be provided upon its hand engaging portion with the lateral down turned side flanges 25 34, to give strength to the same. An aperture 36 is provided in the extreme end of the hand engaging portion of the lever 30, for hanging or otherwise supporting the article holder when not in use.
30. As before mentioned, upon relative movement of the turn table B, upon the supporting or base plate A, the jaws D will be advanced or retracted thereon, due to the cam action of a pair of intersecting slots, 35 engaging each of the pins 24 of individual jaw elements D. It may be desired, therefore, to secure the jaw element D in one position to engage a jaw F, for supporting the same. To this end, a bolt or rivet 40 40 has been provided with a screw threaded end 41 projecting upwardly from the shank 11, and through an arcuate slot 42, struck in the enlarged portion 32, from the pivot 31 as a center. A wing nut 45 has been 45 provided for engagement upon the screw threaded end 41, and for clamping upon the top of the enlarged handle portion 32, whereby the operating lever means C may be clamped in any preferred position with 50 respect to the base plate A.
- Since the article F to be held, will in some cases be unwieldy, the supporting means E has been provided to maintain the article holder in a fixed position. The supporting 55 means E, includes a substantially U-shaped element 45, having one leg or upper plate 46 thereof for riveting or otherwise engaging upon the bottom of the base plate A as by rivets or the like 47. A plurality of arcuate 60 slots 48 will be necessary in the top leg 46, adapted to expose the slots 14 in the base plate A, and permit free reciprocation of the heads 25 of the various sliding pins 24. The bottom leg 50 of the U-shaped element 45 is 65 provided for parallel relation with the leg

46, and provided with a screw threaded aperture 51 therein, adapted to receive a clamp screw 52. The clamp screw 52 is provided with a table or support engaging foot 53, and an operating screw head 54. The opening of the member 45, is disposed 70 opposite to the operating handle means C, whereby the member 45 can readily be inserted over a table or other support.

In operation, the member 45 is slipped 75 over a table or support, and the article holder securely clamped to a table or support by adjusting the screw 52. The jar or other element F is again disposed upon the top of the turn table B, in such position, that 80 the jaws C are extended laterally about its bottom circumference. Upon pivotal movement of the handle lever C, the teeth 33 thereof will engage the teeth 16 of the turn table B, and pivotally move the turntable 85 B on the base plate A. This relative movement of the turntable B on the base plate A, will move the jaws D in contracting circumferential alignment, as above mentioned to engage a side of the article F. Figure 1 of 90 the drawing, shows the jaws D and handle C, prior to contraction of the jaws D to engage the article F. The dotted lines in Figure 1, show the respective positions of 95 the jaws D and handle C, when the jaws D have been contracted to their extreme positions. After the jaws D engage the sides of the article F, the clamp nut 43 can be rotated upon the screw threaded shank 41, until the same engages the handle C and securely clamps the same in its adjusted position with respect to the base plate A, and 100 securely holding the jaws D in engagement with the article F.

Various changes in the shape, size and arrangement of parts, may be made to the form of the invention herein shown and described, without departing from the spirit of the invention or the scope of the claims.

I claim:

1. An article holder, comprising in combination a supporting base plate, a turn table oscillatively mounted on said plate, jaw elements on said turn table and plate, and means on said supporting plate for engaging 115 and oscillating the turn table relative to said supporting plate, for moving said jaw elements relative to each other.
2. An article holder, comprising in combination a supporting base plate, a turn table 120 oscillatively mounted on said plate, jaw elements on said turn table and plate, and means pivotally mounted on said supporting plate engaging the turn table for movement to oscillate the turn table relative to said 125 supporting plate for moving said jaw elements relative to each other.
3. An article holder comprising a base plate having slots therein, a second plate pivotally mounted on said base plate and 130

having slots therein, jaw elements mounted through said slots in said plates, and means on said base plate for engagement with said second plate to oscillate the second plate 5 to move the jaws relative to each other.

4. An article holder, comprising in combination a base plate, a second plate oscillatively pivoted thereto, jaw elements engaging in said first and second mentioned 10 plates, and manually operable rack means pivoted to said base plate engaging said second plate for oscillation thereof for adjusting the relative positions of said jaws.

5. An article holder, comprising in combination a base plate, a turn table pivoted thereon, a handle pivoted to said base plate, intermeshing means on said turn table and pivoted handle, and jaw elements on said turn table for relative movement by operation of said pivoted handle.

6. An article holder, comprising in combination a base plate, a turn table pivoted thereon having teeth segmentally upon a portion thereof, a pivoted handle on said 25 base plate having segmental teeth adapted for intermeshing with said teeth of the turntable, said turntable and base plate having cooperating intersecting slots, and a plurality of jaw elements engaging the slots in

said base plate and turn table, said jaw 30 elements adapted for advancing or retraction by operation of said handle means.

7. An article holder comprising a base plate including a shank and a disc, said disc having slots therein, a second plate of substantially the same size as the disc on said base plate and having slots therein, jaw elements including portions for attachment in the slots of said base and second mentioned plates, and means pivotally mounted 40 on the shank portion of said base plate and engaging said second mentioned plate to oscillate the same for relative movement of said jaw elements.

8. An article holder comprising in combination a base plate, a turntable pivotally mounted on said base plate, jaw elements on said turn table, an operating handle structure pivoted to said base plate and engaging said turn table for oscillation of said 50 turntable, said handle having a slot therein, clamping means in said base plate for adjustment to engage said handle through the slot therein to maintain said handle in adjusted position on said base plate for maintaining said jaws in a fixed position.

DON CARLOS WISENBERG.
